F. MOSSBERG

REEL

Filed March 12, 1927

UNITED STATES PATENT OFFICE.

FRANK MOSSBERG, OF ATTLEBORO, MASSACHUSETTS, ASSIGNOR TO MOSSBERG PRESSED STEEL CORPORATION, OF ATTLEBORO, MASSACHUSETTS, A CORPORATION OF MASSACHUSETTS.

REEL.

Application filed March 12, 1927. Serial No. 174,851.

This invention relates to a spool or reel of sheet material; and has for its object to construct the heads of the reel so that the same may be stacked vertically with their axes 5 out of alignment without the pile tumbling.

A further object of the invention is to attach separate members to the outer surface of each of the spool heads of a dimension to present their outer portions in a single 10 plane at right angles to the axis of the spool to support the head of the adjacent spool so that the axes of the adjacent spools will be parallel even tho the out of axial alignment.

A still further object of the invention is to 15 provide radially-disposed ribs located adjacent the reinforced periphery of the head of a dimension so that their outer surfaces will be in substantially the same plane as the reinforcement of the periphery of the 20 head so that the spools may be stacked vertically end to end with their axes in staggered relation.

With these and other objects in view, the 25 invention consists of certain novel features of construction, as will be more fully described, and particularly pointed out in the appended claims.

In the accompanying drawings:

Figure 1 is a side elevation of a vertically 30 disposed stack of spools showing the same with their axes staggered one relative to the other and yet the spools are supported in such a way that their axes are all vertical to the supporting base and there is no danger 35 of the stack tumbling.

Figure 2 is a plan view of one of the heads.

Figure 3 is a side elevation broken away 40 so as to show one of the heads partly in section.

Figure 4 is a perspective view of one of the radial ribs attached to the outer surface of the head.

Figure 5 is a plan view of a head with a modified form of rib attached thereto.

Figure 6 is a side elevation of the same 45 with portions broken away.

Figure 7 is a perspective view of one of the radially-disposed ribs of modified form shown in Figures 5 and 6.

Figure 8 is a perspective view of a still 50 further modified construction partly broken away to better illustrate the same shape.

It is found in practice desirable to provide

spools or reels which may be stacked vertically one on the other without danger of 55 the same tumbling if their axes are slightly out of line and in order to accomplish this result in spools which have their edges reinforced by outwardly-extending portions, I have provided separate parts which may be 60 attached to the outer surface of the heads adjacent the periphery thereof to extend the bearing surface of this reinforced edge to obtain such result; and the following is a 65 detailed description of the present embodiment of this invention and showing one means by which these advantageous results may be accomplished:—

With reference to the accompanying drawings, 10 designates the body portion of 70 a spool or reel having heads 11 attached thereto in any suitable manner. Each of these heads is of sheet metal construction with its periphery suitably reinforced by deflecting the same outwardly as at 75 12 which may be in the form of a roll, as illustrated in Figures 3 and 6, or in the form of a right-angularly extending flange 13, as illustrated in Figure 8. This reinforced periphery provides a relatively narrow bearing surface which is insufficient to support the spools in a vertical stack with their axes in staggered relation, and in order to prevent one spool when placed upon the 80 top of another from inclining its axis to the vertical, I have provided radially-extending supporting ribs 14, the ends 15 of which are positioned adjacent the reinforced edge 12, the ribs being of sufficient length to present 85 the desired surface required.

These separate ribs are attached to the outer surface of the heads by spot welding, riveting or in any other suitable manner and are positioned in spaced relation about the surface of the head in a number to accomplish the desired result. The ribs present a portion of their outer surface 16 in substantially the same plane as the outer surface of the reinforced edge 12 whereby an enlarged surface at right angles to the axis 100 of the spool is presented for the stacking of the reels in vertical relation without the necessity of aligning the axes of adjacent spools with each other.

Each of the ribs 14 is of angle iron, as 105 illustrated in Figure 4, but if desired the

ribs may be shaped as illustrated at 15, in Figure 7, and attached by suitable rivets 18 at one end to the outer surface of the head with their other end portions 19 resting upon the inner edge of the rolled reinforcing periphery 12 as a support therefor.

In the type of reel heretofore illustrated the heads are each provided with a central deflected portion 20 having radially disposed 10 deflected portions 21 extending therefrom for suitably stiffening the head. The deflected portion 20 has its outer surface 22 located in substantially the same plane as the reinforcing edges or below the same so 15 as not to interfere with the end-to-end position of the spools in being vertically stacked one upon the other.

In some instances, instead of using radially disposed ribs I may provide an annular 20 member which extends inwardly to increase the bearing surface of the head and presents sufficient support for the positioning of the spools one upon the other for the purposes heretofore mentioned. A flange portion 25 25 is secured to the annular member to nest within the flange 13 on the head to assist in supporting the same and holding it in position.

It will be seen that I have provided a 30 construction by which spools may be stacked one upon the other without danger of tumbling even though the spools are slightly staggered, which is found to be of great advantage in practice for storage and the like.

The foregoing description is directed solely towards the construction illustrated, but I desire it to be understood that I reserve the privilege of resorting to all the mechanical changes to which the device is 40 susceptible, the invention being defined and limited only by the terms of the appended claims.

I claim:

1. A sheet metal reel comprising a body 45 having a head at each end, each of said heads having its periphery outwardly deflected to stiffen the same, and separate members attached to said heads adjacent and inwardly of the periphery thereof and of a 50 dimension to present a portion in substantially the same plane as the edge of said deflected periphery whereby the reels may be stacked vertically end-to-end with their axes in staggered relation without tumbling.

2. A sheet metal reel comprising a body having a head at each end, each of said heads having its periphery outwardly deflected to stiffen the same, and separate radially disposed members attached to the outer 60 surface of said heads adjacent the periphery thereof having portions in the same plane as said deflected periphery, whereby the reels may be stacked vertically end-to-end with their axes in staggered relation but 65 parallel to each other.

3. A sheet metal reel comprising a body having a head at each end, each of said heads having its periphery and portions about the center outwardly deflected to stiffen the same, and separate radially-extending members attached to the outer surface of the heads positioned adjacent the periphery and in substantially the same plane with the outer edge thereof to prevent the tilting of adjacent reels when vertically 70 stacked end-to-end.

4. A reel comprising a body having a sheet metal head at each end, each of said heads having its periphery outwardly deflected to stiffen the same, with radially 80 extending portions extending outwardly towards said periphery and terminating at a distance therefrom, and supporting means extending inwardly from the said peripheral portion of the said heads, and having a 85 bearing surface in the plane of the outer surface of said deflected periphery.

5. A reel comprising a body having a sheet metal head at each end, each of said heads having its periphery outwardly deflected to stiffen the same, with radially 90 extending portions extending outwardly towards said periphery and terminating at a distance therefrom, and supporting means extending inwardly from the said peripheral portion of the said heads, and having a bearing surface in the plane of the outer surface of said deflected periphery, the outer 95 surfaces of the said supporting means lying in substantially the same plane as the outer surfaces of the said peripheries so as to permit said reels to be vertically stacked 100 end-to-end with their axes out of line but substantially vertically disposed to the supporting base.

6. A reel comprising a body having a sheet metal head at each end, each of said heads having its periphery outwardly deflected to provide a raised surface, radially 110 extending portions formed on the said heads, said portions terminating at a distance from the periphery thereof, and radially disposed ribs mounted on the said heads and extending inwardly from the peripheries thereof, said ribs being interposed between the said 115 radially extending portions.

7. A reel comprising a body having a sheet metal head at each end, each of said heads having its periphery outwardly deflected to provide a raised surface, radially 120 extending portions formed on the said heads, said portions terminating at a distance from the periphery thereof, and radially disposed ribs mounted on the said heads and extending inwardly from the peripheries thereof, said ribs being interposed between the said 125 radially extending portions, the upper surfaces of the said ribs lying in substantially the same plane as the upper surface of the said peripheries.

8. A reel comprising a body having a sheet metal head at each end, each of said heads having its periphery outwardly deflected to stiffen the same, radially disposed 5 stiffening means formed on each head and terminating at a distance from the said periphery, and means carried by said heads and extending inwardly from the said periphery thereof for presenting a bearing surface 10 whereby a plurality of the reels may be vertically stacked.

9. A reel comprising a body having heads at its ends, the periphery of each of said heads being flanged, stiffening means formed 15 on the heads and extending towards said flange but terminating at a distance therefrom, and a plurality of bearing members

extending inwardly from said flange and in the plane with the edge thereof.

10. A reel comprising a body having heads at its ends, the periphery of each of said heads being flanged, stiffening means formed 20 on the heads and extending towards said flange but terminating at a distance therefrom, and a plurality of bearing members 25 extending inwardly from said flange and in the plane therewith, said bearing members being interposed between the said stiffening means and providing a single plane surface whereby a plurality of the reels may be vertically stacked. 30

In testimony whereof I affix my signature.

FRANK MOSSBERG.
